UNITED STATES PATENT OFFICE

ARTHUR BROWN, OF LAKE CITY, IOWA

WORK-HOLDING DEVICE

Original application filed May 11, 1929, Serial No. 362,376. Divided and this application filed May 19, 1930. Serial No. 453,781.

My invention relates to certain new and useful improvements in work holding devices which are adapted particularly for plumbers use.

5 The invention seeks to provide a device for the purpose stated of simple and inexpensive construction that can be easily and cheaply manufactured and will readily serve its intended purpose.

10 Another object of the invention is to provide a device for supporting rods, pipes, flat bars or boards and holding the same against movement while operating thereon.

15 Other objects will in part be obvious and in part be pointed out hereinafter.

To the attainment of the aforesaid objects and ends, my invention consists in the novel features of construction and in the combination, connection and arrangement of parts, 20 hereinafter more fully described, and then pointed out in the appended claims.

In the drawings:

Figure 1 is a top plan view of the device, the chain or flexible element being omitted.

25 Figure 2 is a side elevation of the same, the chain or flexible element being omitted.

Figure 3 is a transverse vertical section on the line 3—3 of Figure 2, the chain or flexible element being shown as used for the purpose 30 of holding down a bar in the crotch formed by the members 10.

Figure 4 is an enlarged detail cross sectional view of a portion of the device, showing how the same may be used for holding a board 35 or flat bar.

Figure 5 is a detail side elevation of the device showing the same in use for holding a board as in Figure 4, on which board a vise or other working implement may be mounted.

40 In the drawing in which like numerals of reference indicate like parts in all of the figures, it will be seen that the device comprises a frame consisting of end transverse bars 1—1, and an intermediate transverse bar

45 3 connected by crossed bars 2, the same being secured at proper places by rivets 4 as indicated. Mounted on the base are standards composed of flat bars 5 having foot portions 6 riveted to the base. There are three sets 50 of bars 5, the two end ones and an interme-

diate set. The bars of a set converge and then extend vertically upward as at 7 where they again diverge at 10 to constitute the saddle members. Secured to one end standard and to the intermediate standard at one side is a combined brace and stop bar 8, the same being riveted or otherwise secured in place as at 9, the purpose of which will presently appear.

55 The diverging arms 10 of the standard bars have holes 11 through which may be passed pins 12 on which an article-to-be-supported 30 may rest while confined against sidewise movement by the saddle arms 10.

60 Connecting the three standards on the same side is a longitudinal tie bar 15. The intermediate and the adjacent end standards are further braced by cross bars 13 that are riveted at 14 to the standards.

65 A lever 22 is pivoted to an ear 21 that is secured to the support and it has a catch tooth 23 for association with the notches 25 of a catch plate 24 that is secured to one of the standards composed of the bars 5.

A spring 26 may be secured to the lever 22 75 and another spring 27 secured to the ear 21, these springs having hook ends to which the chain or flexible element 28 may be connected.

29 represents a rod, bar, pipe or other article held on the saddles 10 by the chain 28 80 passing over the same and being placed under tension by pressing down on the lever 22 and causing the catch tooth 23 to interlock with one of the notches 25 of the catch plate 24.

85 When it is desired to secure a board or flat bar on the support as when it is desired to mount a vise 31 for example, the cross pins 12 are placed in the proper openings 11 and the board 30 laid thereon. The chain 28 is then passed over the board as indicated in Figures 4 and 5 and the lever is pressed down tightly and latched in its tensioned position, thereby securely holding the board 30 on the support.

90 This application is a division of my application filed May 11, 1929, Serial No. 362,376. 95

From the foregoing description, taken in connection with the accompanying drawings, it is thought the construction and uses of my invention will be clear to those skilled in the art to which it relates, and I desire it under- 100

stood that slight changes in the details of construction may be made without departing from the scope of the invention and the appended claims.

What I claim is:

- 5 1. A work holding device comprising a frame composed of a base and end standards which includes legs and diverging saddle arms, a lever fulcrumed at one end to one leg of a standard, a rack plate secured to the other leg of the same standard to cooperate with said lever, a spring, one end of which is anchored to said frame adjacent the base, a flexible element, one end of which is secured to the other end of said spring and which is adapted to pass over an article located in said saddle arms, a second spring, one end of which is anchored to said lever, said flexible element having its other end secured to the other end of said second spring.
- 10 2. In a work holding device, a base, end standards projecting upwardly from said base and each comprising a front and a back bar secured to the base and converging upwardly and inwardly, each leg having a vertical portion, said vertical portions extending in contact with one another, means securing said bars together at said contacting portions, said bars having diverging upwardly extending portions constituting a saddle, each upwardly diverging portion having a series of horizontal pin holes, those of the bars of a standard aligning with each other, a pin located in said holes of a standard and extending from one upwardly diverging portion thereof to the other diverging portion thereof; and means to hold an object in place on said pins in said saddle.

ARTHUR BROWN.
